(57) **CLAIM**

We claim the ornamental design for an electric oven range, as shown and described.

DESCRIPTION

FIG. 1 is a top, front and right-side perspective view of an electric oven range showing our new design;

FIG. 2 is a bottom, front and right-side perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is another front elevation view of the electric oven range shown in an environment of use with a touch screen on the right portion; and,

FIG. 10 is a front elevation view of the electric oven range shown in another environment of use.

The evenly-spaced broken lines shown in FIGS. 1-10 depict portions of the electric oven range or environmental structure that form no part of the claimed design. The dot-dot-dash broken line showing the border and the remaining broken line except for the subject article in FIG. 10 illustrate environment and form no part of the claimed design.
